UNITED STATES PATENT OFFICE.

FAXON DEAN ATHERTON, JR., OF SAN FRANCISCO, CALIFORNIA.

COPYING DEVICE.

Application filed April 13, 1922. Serial No. 552,282.

To all whom it may concern:

Be it known that I, FAXON DEAN ATHERTON, Jr., a citizen of the United States, residing in the city and county of San Francisco and State of California, have invented a new and useful Improvement in a Copying Device, of which the following is a specification.

My invention relates to improvements in copying devices for the photographic copying of printed characters and the like, wherein in a light dispersing element and a plurality of sensitized webs are mounted within a holder and arranged to be withdrawn for placing upon a surface bearing subject matter to be copied.

The primary object of my invention is to provide an improved copying device affording compactness of structure and ease of application.

Another object is to provide an improved device of the character described adapted to facilitate the placing and withdrawal of sensitized webs for copying purposes.

A further object is to provide a device arranged to normally protect sensitized webs supplied therein from exposure to light.

A still further object is to provide an improved device having means for normally preventing the complete withdrawal of the light dispersing elements and the webs thereby insuring against the over-exposing of the web.

I accomplish these and other objects by means of the device disclosed in the drawings forming a part of the present specification wherein like characters of reference are used to designate similar parts throughout said specification and drawings and in which:

Fig. 1 is a plan view of my improved copying device, portions being broken away to disclose the arrangement thereof.

Fig. 2 is a similar view with the light dispersing element and a sensitized web withdrawn to the operative position.

Fig. 3 is an enlarged longitudinal vertical section of the device.

Fig. 4 is a similar section of another form of holder in which sensitized webs are mounted upon both sides of the light dispersing element.

Fig. 5 is an enlarged sectional view of a sensitized web retainer.

Fig. 6 is an enlarged detail showing one

means for preventing the complete withdrawal of the webs and light dispersing member from the holder.

Referring to the drawings the numeral 1 is used to designate in general a holder made of any suitable opaque material. A light dispersing element 2 is slidably mounted within the holder 1, said element being preferably a flat plate of ground glass, mounted within a frame 3. Within the holder 1 adjacent the element 2 are slidably mounted a plurality of webs 4 of sensitized print paper preferably of the character commonly termed "gas light" paper, said webs being carried by retainers 6 engaging the edges thereof. Tabs 7 are secured upon one end of the retainers 6 to extend outwardly at one end of the holder, the other end of said retainers being open as at 5 to permit the webs 4 to be inserted and removed therefrom.

The holder 1 is provided with a partition 8 separating the element 2 from the sensitized webs 4. A flap 9 is secured upon the holder 1 to fold over the open end to exclude the light from the holder when not in use.

The inner ends of the retainers 6 and the frame 3 are provided with shoulders 11 adapted to engage catches 12 mounted upon the edges of the holder 1 adjacent the open end thereof to normally prevent the complete withdrawal of the webs 4 and element 2 from the holder, said catches being arranged to be turned away from the open end as shown in dotted lines in Fig. 2 when it is desired to remove the retainers 6 and frame 3 from the holder.

The operation of my improved copying device is as follows: Webs of sensitized paper are cut to the proper size and inserted into the retainers 6 through the open ends thereof. The retainers are then inserted into the holder 1 with the tabs 7 at the open end thereof and with the sensitized side of the webs 4 turned away from the element 2. The catches 12 are then turned to the operative position shown in Fig. 2 of the drawings and the flap 9 fastened by means of a suitable fastener 13 to close the open end of the holder 1 and exclude light therefrom until such time as it is desired to utilize the device for copying.

When it is desired to make a copy of a printed subject such as a check, drawing, or a paragraph from a printed article, or of a signature, photograph or other device

of a kindred nature, the flap 9 is moved to permit withdrawal of the light dispersing element 2 from the holder. The device to be copied is laid upon a flat surface and the holder placed adjacent thereto, the light dispersing element 2 and one of the sensitized webs being then withdrawn to cover the portion of the subject matter which it is desired to copy. The sensitized side of the web is applied next to the subject matter to be copied and is held firmly thereagainst by means of pressure applied upon the element 2 or the frame 3, the web being preferably withdrawn simultaneously with the light dispersing element 2 by means of the tab 7 to prevent the entrance of light between said element and the web. Light is now directed upon the upper exposed surface of the element 2, said light being transmitted through said element 2 and the web 4 upon the subject matter to be copied. The element 2 as above stated is preferably made of ground glass in order that the light passing therethrough may be diffused to obtain an even exposure of the web, but any material adapted to transmit light and hold the web in close contact with the subject matter to be copied may be substituted. The light rays striking white or light colored portions of the subject are reflected back upon the sensitized web while rays striking dark portions of the subject are absorbed or reflected to a lesser degree. In this manner the portions of the web adjacent the light portions of the subject are more quickly acted upon than those portions above the dark portions of the subject. When the web has been exposed in this manner for a suitable period of time the web and element 2 are moved back into the holder. The web may be subsequently removed at any time convenient to the operator and developed after the fashion of the ordinary photographic print in the well-known manner.

The print thus obtained is a negative of the subject matter copied, that is, the device is reversed and the light portions of the subject appear dark and the dark portions appear light upon the copy. If it is desired to obtain a positive copy, the negative obtained in the above manner is copied in the manner above described, the colors and arrangement being thus again reversed to give a positive copy of the original subject.

Each of the webs 4 may be exposed in the manner above described to obtain copies of various subjects as desired, the several webs being removed and developed together at any convenient time.

In Fig. 3 I have illustrated the device as provided with webs positioned upon only one side of the element 2; however, similar webs may be applied upon each side of the

light dispersing element as shown in Fig. 4, the number of such webs being limited only by the ability of the operator to obtain a close contact between the web and the subject matter to be copied. In Fig. 4 I have also shown the holder 1 as provided with a removable cap 14 closing the open end thereof in place of the flap as shown and described in Fig. 3.

The above construction affords a neat and compact device which may be readily carried in the pocket and without inconvenience to the operator. However, I do not wish to limit myself to the precise construction disclosed as clearly the form and arrangement of the several elements may be modified in numerous ways without departing from the spirit of my invention.

Having thus described my invention what I claim as new and desire to secure by Letters Patent is:

1. A copying device comprising a holder; a light dispersing element slidably mounted within the holder; and a web of sensitized paper slidably mounted within the holder adjacent the light dispersing element, said web and light dispersing elements being arranged to be withdrawn from the holder for placement upon subject matter to be copied. 95

2. A copying device comprising a holder; a light dispersing element slidably mounted within the holder; and a web of sensitized paper slidably mounted within the holder adjacent the light dispersing element, said web and light dispersing elements being arranged to be simultaneously withdrawn from the holder for placement upon subject matter to be copied. 100

3. A copying device comprising a holder; a light dispersing element slidably mounted within the holder; a web of sensitized paper slidably mounted within the holder adjacent the light dispersing element, said web and light dispersing elements being arranged to be simultaneously withdrawn from the holder for placement upon subject matter to be copied; and means for limiting the outward movement of the light dispersing element and the web to normally prevent complete removal thereof from the holder when withdrawn for copying purposes. 110

4. A copying device comprising a holder; a light dispersing element slidably mounted within the holder; a web of sensitized paper slidably mounted within the holder adjacent the light dispersing element, said web and light dispersing elements being arranged to be withdrawn from the holder for placement upon subject matter to be copied; and means for normally retaining said light dispersing element and web within the holder and for excluding light therefrom. 125 130

5. A copying device comprising a holder; a light dispersing element slidably mounted within said holder and arranged to be withdrawn therefrom to an operative position; a plurality of sensitized webs slidably mounted within the holder adjacent the light dispersing member, said webs being independently movable simultaneously with the light dispersing element to the operative position thereof. 10
6. A copying device comprising a holder; a light dispersing element slidably mounted within the holder; and a plurality of sensitized web retainers slidably mounted within the holder adjacent the light dispersing element, said retainers being independently movable for withdrawal to an operative position simultaneously with the light dispersing element for placing a sensitized web supplied therein upon subject matter to be copied. 15
7. A copying device comprising a holder; a light dispersing element slidably mounted within the holder; a plurality of sensitized web retainers slidably mounted within the holder adjacent the light dispersing element, said retainers being independently movable for withdrawal to an operative position simultaneously with the light dispersing element for placing a sensitized web supplied therein upon subject matter to be copied; and means for limiting the outward movement of said retainers and light dispersing element to normally prevent complete removal thereof from the holder when withdrawn to the operative position for copying purposes. 20
8. A copying device comprising a holder; a light dispersing element slidably mounted within the holder and adapted for outward movement therefrom to an operative position; a plurality of retainers slidably mounted within the holder adjacent the light dispersing element, said retainers being each arranged to receive and removably engage a sensitized web and adapted for independent outward movement to the operative position simultaneously with the light dispersing element; and means arranged to normally retain said light dispersing element and said retainers within the container and to exclude light therefrom. 25
9. A copying device comprising a holder; a light dispersing element slidably mounted within the holder and adapted for outward movement therefrom to an operative position; a plurality of retainers slidably mounted within the holder adjacent the light dispersing element; said retainers being each adapted to receive and removably engage a sensitized web and adapted for independent outward movement simultaneously with the light dispersing element to the operative position; shoulders formed upon the inner ends of the light dispersing element and the retainers; and means mounted upon the holder to normally engage said shoulders and prevent further outward movement when the light dispersing element and the retainers have been moved to the operative position. 30
